UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,149,586.

Specification of Letters Patent. Patented Aug. 10, 1915.

Application filed May 31, 1911. Serial No. 630,389.

To all whom it may concern:

Be it known that I, CHARLES J. KLEIN, a citizen of the United States, residing at Milwaukee, in the county of Milwaukee and 5 State of Wisconsin, have invented new and useful Improvements in Electric Switches, of which the following is a full, clear, concise, and exact description, reference being had to the accompanying drawing, forming 10 a part of this specification.

My invention relates to electric switches.

One of the objects of my invention is to provide an improved electric switch.

A further object of my invention is to 15 provide an improved switch unit which is complete in itself and capable of being readily inserted in various forms of switching devices and which is of an exceedingly compact, serviceable and unitary construction.

Other objects and advantages of my invention will hereinafter appear.

In the accompanying drawings I have 20 illustrated two forms which my invention 25 may assume in practice. My invention is not however limited in its use to these particular forms which have been chosen for purposes of illustration, but is capable of being used in various other relations and of 30 assuming various other forms.

In the views of the drawing, Figure 1 shows a perspective view of a switch unit. Fig. 2 shows a transverse sectional view of the switch unit in position in a surface 35 switch casing. Fig. 3 shows a longitudinal sectional view of the construction shown in Fig. 2. Fig. 4 shows a modified form of unit in position in a modified form of casing. Fig. 5 shows a side elevation of the 40 unit shown in Fig. 4 with a transverse section of the casing.

The construction shown in Figs. 1 to 3 will be first considered. The switch mechanism employed is preferably of the type 45 described in my previously granted Patent No. 985,241 patented February 28, 1911. This mechanism includes a reciprocable cam member 1 having the conformation of a double frustum positioned base to base and 50 carried upon a centrally disposed threaded shaft 2 carrying upon its opposite ends removable push buttons 3 of a smaller diameter than the diameter of the ends of the cam member. In a preferred form the shaft 2 is fixed within one of the push but- 55 tons and removable with the same. A contactor 4 preferably of the type described in my co-pending application Serial No. 630,388, filed May 31, 1911, and containing a helical spring 5 is arranged to be reciprocated upon movement of the cam member to make or break the electrical circuit with a quick snap action when the garter spring moves across the crest of the cam 1.

The switch mechanism is carried in a suitable frame which is provided with means for carrying the parts of the switch mechanism and guiding and limiting the same in their operations, as well as means for conveying the current to the contact parts so 70 that when in position in this frame the switch mechanism forms a complete unit. In a preferred form the frame is provided with two end portions 6 and 7 which are adapted to permit the reciprocation of the 75 push buttons through the same and serve to establish the limits of travel of the operating parts and to provide suitable contact surfaces with which the moving contact member may engage. The end 6 on the 80 frame is preferably formed of stamped sheet metal of the construction shown in Fig. 1, being provided with a tapering portion or extension 8 bent outward as illustrated in that figure and provided with a 85 flange 9 at its end surrounding a perforation through which one of the push buttons 3 extends. This perforation is of a sufficient size to permit the push button to be reciprocated through the same, but is not of a sufficient size to permit the tapered end of the 90 cam member to move through the same so that the flange 9 serves as a stop for the cam member in this position. In a preferred form side pieces 10 are formed integral with the end member 6. These sides pieces connect the end member 6 with the end member 7 and preferably extend above and below the contactor 4 as illustrated in Fig. 1. The end member 7 is preferably formed of 100 insulating material such for example as molded stone, rubber or fiber, and is of a substantially rectangular cross section. As illustrated in Fig. 3 this end member is provided with a central tapered perforation 11 105 arranged to receive the end of the cam member 1. As shown in Fig. 1 this end member is also provided at its sides with suitable slots 12 arranged to receive the reduced ends 13 of the sides 10. In order to secure 110

the extremities of the parts 13 to the end member 7 and so attach the parts of the frame as to make it form a unitary construction, I preferably provide a binding plate 14 on the outer surface of the end member 7 as shown in Figs. 2 and 3. This end member 14 is provided with a central perforation arranged to permit the reciprocation of the push button through the same, but which is not of sufficient size to permit the tapered end of the cam 1 through the same so that this binding plate serves as a stop for the cam member. In a preferred form the ends of the reduced portions 13 of the sides 10 are received in suitable openings near the ends of the plate 14 and are spread or riveted in the same as illustrated at 15 in Fig. 2. The terminal members for the switch are carried on the inner surface of the end member 7 and preferably consist of terminal plates 16 arranged parallel to each other on opposite sides of the member 7 extending substantially at right angles to the sides 10. The plates 16 are preferably carried in suitable grooves 17 in the sides of the member 7 and in a preferred form the outer edges of the member 7 are cut away as illustrated at 18 to permit the edge of the contactor to move along the outer surface of the terminal plates. In a preferred form the terminal plates 16 are provided with integral projections or legs 19 which pass through the member 7 and are preferably riveted to the outer surface of terminal plates 20. As illustrated in Fig. 2 these terminal plates 20 are preferably of a conformation adapted to fit around a rounded portion 21 on the binding plate 14 which surrounds the perforation through which the push button is reciprocated and the terminal plates 20 are also preferably set in suitable recesses 22 on opposite sides of the outer surface of the member 7. The terminal plates 20 are also provided at their outer ends with binding screws 23 arranged to be suitably connected to a circuit and are also equipped with angularly disposed lugs 24 to enable a ready connection of the conductors to the binding screws.

In Figs. 2 and 3 I have illustrated my improved switch unit in position in a surface switch casing of substantially rectangular shape. As illustrated the unit is so placed in a suitable base 25 that one of its sides 10 lies flat upon the bottom of the same in a suitable recess 26. In a preferred form this side 10 is secured to the bottom of the chamber by a screw 27 arranged to engage in a threaded recess 28 in the side 60 and having its head resting in a suitable recess in the bottom of the base 25. When the unit is in this position in the base, the terminal plates 20 rest on the side walls of the chamber 26 and in a preferred form the base is provided with suitable recesses 30

extending from the bottom of the base up through the walls to points adjacent the binding screws so that the conductors may readily be brought in through the base in order to be attached to the binding screws. 70 In a preferred form the lower ends of the recesses 30 are slightly rounded as illustrated in Fig. 2 in order to prevent the wear on the conductors. Since the end of the binding plate 14 may extend beyond the 75 portion 13 of the side 10, a suitable recess 31 may be provided in the bottom of the chamber 26 near one end of the same to house the end of this plate as illustrated in Fig. 3. In order to receive the extension or tapering 80 portion 8 on the end 6 of the frame, the end wall of the chamber 26 may be cut away as shown at 32. In order to protect the parts of the switch unit when in position in the base, a suitable cover may be provided. As 85 illustrated in Figs. 2 and 3 this cover may consist of an outer metallic casing 33 of substantially rectangular cross section arranged to have its edges rest on flanges 34 formed around the edges of the base 25. In 90 a preferred form this cover 33 is provided with an insulating lining 35 which is crimped in the cover and fits snugly within the same and the cover and lining are provided with suitable slots 36 arranged to permit the 95 same to be slipped over the push buttons, and suitable means such as a screw 37 for securing the cover in position. In a preferred form the screw 37 extends through a suitable perforation in the top of the cover 100 and engages in a threaded perforation in the upper side 10 of the frame.

In Figs. 4 and 5 I have illustrated a modified form of unit. In this construction the operating parts of the mechanism are substantially the same as those heretofore described. However in this instance the sides of the frame 10 are held in position and secured to the end member 7 by a binding plate of a different construction from that heretofore described, in this instance the binding plate 38 having an arched portion which is provided with a central perforation and flange similar to the perforation and flange of the extension 8. In this form the 110 terminal members are also of a different construction since instead of being provided with terminal plates on the back of the end member 7 they are provided with lateral extensions 39 which are bent substantially at 115 right angles to the body portion of the terminal members and are provided at their ends with binding screws and connecting ears similar to those heretofore described. In applying this construction to service I 120 may place the unit in a tubular insulating shell 40 having suitable perforations 41 in its opposite side. When the unit has been placed in position in the shell so that the 125 perforations in the opposite ends of the 130

frame register with the perforations in the shell 40, the push buttons 3 are screwed in position and the switch mechanism is accurately held in the desired place in the shell. 5 Thus it is seen that the switch mechanism may be readily inserted in any shell or receptacle by simply boring holes in the opposite sides of the same, inserting the switch mechanism until the holes register with the 10 perforations in the frame of the switch mechanism and later screwing in the push buttons. It is obvious that any form of receptacle may be used which is desired and that when for instance an insulating shell is 15 used the entire shell with the unit switch mechanism inside of it may if desired be inserted in a suitable outer receptacle such for example as a tube or handle which has previously been provided with suitable oppositely disposed perforations and the entire 20 mechanism fixed in position by screwing on the push buttons.

When it is desired to operate the switch mechanism one of the push buttons is 25 pushed in and the contactor is thrown either to circuit making or breaking position. As the push button is pushed in the cam member is moved to one of the limits of its travel either against the flange 9 on the end member 30 6 or the edge of the perforation in the binding plate 14. As the cam member is moved the contactor 4 is reciprocated in an opposite direction moving with a quick snap action in this direction when the garter 35 spring is passed over the crest of the cam member. This contactor reaches one of its limits of travel either against the inner surface of the end member 6 as shown in Fig. 1 or against the terminal contacts 16 as shown 40 in Fig. 3 at substantially the same time that the cam member reaches its limit of travel. Thus it is seen that the frame comprising the end members 6 and 7 and their connecting parts serves as a means for guiding the 45 operating member and a means for limiting the movement of the operating member and the movable contact member.

By my improved construction I have provided a very compact switch unit which is 50 capable of being used in various relations wherever a single unitary construction is desired. Further the unit is of such a compact and serviceable construction that the switch mechanism occupies a very small 55 space and is adapted to long use in service. As illustrated in the various forms described in this application, the unitary switch mechanism herein described may find various uses in the art, and may be readily adapted 60 with slight modifications to any use wherein in a compact and unitary construction is desired.

While I have in this application described the specific construction of several 65 forms which my invention may assume in

practice, I have chosen these forms only as means of illustrating the principle of my invention, and I do not wish to be limited to the specific constructions herein described, but rather wish to cover all of the various 70 modifications of the same which my invention is capable of assuming and which fall within the scope of the appended claims.

What I claim as new and desire to secure by Letters Patent is as follows:—

1. An electric switch unit comprising end members, means connecting the same to form a frame, an insulating block carried in one end of said frame, contacts carried by said block, and a switch mechanism movable in 80 said frame to engage said contacts.

2. An electric switch unit comprising end members, means connecting the same to form a frame, an insulating block carried in one end of said frame, contacts carried by 85 said block, a snap switch mechanism movable in said frame to engage said contacts, and terminal members for said switch mechanism.

3. An electric switch unit comprising end 90 members, means connecting the same to form a frame, an insulating block carried in one end of said frame, contacts carried on said insulating block, a snap switch mechanism movable in said frame to engage said 95 contacts, and terminal members for said switch mechanism carried by said block.

4. An electric switch unit comprising end members, means connecting the same to form a frame, an insulating block carried in 100 one end of said frame, contacts carried by said block, and a snap switch mechanism movable in said frame to engage said contacts, said switch mechanism having its operating member guided and limited in its 105 movement by said frame.

5. An electric switch unit comprising end members, means connecting the same to form a frame, an insulating block carried in one end of said frame, contacts carried on 110 said block, and a snap switch mechanism movable in said frame to engage said contacts, said switch mechanism having its operating member extending through said end members and said insulating block.

6. An electric switch unit comprising an end member, a substantially U shaped member having its ends extending through the ends of said end member and co-operating therewith to form a frame, an insulating 120 block carried in one end of said frame, contacts carried on said insulating block, and a snap switch mechanism movable in said frame to engage said contacts.

7. An electric switch unit comprising end 125 members having openings therein, side members connecting the same to form the frame, an insulating block carried in one end of said frame, contacts carried by said insulating block, and a snap switch mechanism 130

movable in said frame to engage said contacts, said switch mechanism having its operating member passing through said block and said end members and guided and limited in its movement by the latter.

8. In an electric switch device, a push button operated snap switch mechanism, end members guiding and limiting the movement of said switch mechanism, side members connecting said end members to form a frame, and a two-part casing attached to and inclosing said switch mechanism.

9. In combination, a substantially flat base having a conductor inlet therein, a switch unit carried thereby, said switch unit having its terminals adjacent said inlet, and a cover for said switch unit, said cover and said base each being removably attached to said unit.

10. In combination, a base having a recess in one of its faces and conductor grooves communicating therewith, a switch unit set in said recess and having its terminals adjacent said conductor grooves, and a cover for said switch unit fitting snugly around the walls of said recess, said cover and said base being attached to opposite sides of said unit.

11. In combination, a base having a recess in one of its faces and a pair of parallel ver-

tically extending recesses communicating therewith, a switch unit comprising a frame and a switch mechanism movable therein, said switch unit being set in said recess in the face of said base and having its terminals adjacent said vertically disposed recesses, and a cover for said switch unit snugly fitting around the walls of said recess, said cover and said base being attached to said unit frame on opposite sides of the same.

12. In an electric switch device, a reciprocating cam member having removable push buttons of a reduced diameter, an end member arranged to permit one of said push buttons to move through the same and provided with an extension having a central perforation and a flange around the same, a second end member having a central perforation arranged to receive the opposite ends of said cam member, and means for connecting said end members and limiting the movement of said cam member in one direction.

In witness whereof, I have hereunto subscribed my name in the presence of two witnesses.

CHARLES J. KLEIN.
